UNITED STATES PATENT OFFICE.

HUGO LOEWENBACH, OF HARTLAND, WISCONSIN, ASSIGNOR TO AUTOMATIC BOWLING ALLEY CO., OF MILWAUKEE, WISCONSIN.

GAME APPARATUS.

1,392,586.

Specification of Letters Patent.

Patented Oct. 4, 1921.

Application filed December 29, 1919. Serial No. 347,933.

To all whom it may concern:

Be it known that I, HUGO LOEWENBACH, a citizen of the United States, and resident of Hartland, in the county of Waukesha and State of Wisconsin, have invented certain new and useful Improvements in Game Apparatus; and I do hereby declare that the following is a full, clear, and exact description thereof.

10 My invention pertains to new and useful improvements in pin setting mechanism for game apparatuses.

The primary object of the invention is to simplify and cheapen and otherwise improve the structure illustrated in my Patent No. 1,239,280, issued Sept. 4, 1917.

Specifically the improvements to which this invention relates are a novel means for attaching the several pins to their resetting 20 cords, means for more accurately and quickly returning the upset pins from their prone to their upright positions, means for preventing wear between certain parts of the resetting mechanism and the pins, and 25 means for quickly and efficiently adjusting the individual pins with respect to the resetting mechanism.

A further important object of the invention resides in a ball return chute for use 30 with my other features when the same are incorporated in a table game. The particular advantage of this return chute consists in the fact that it may be folded within the body of the table so that the latter can be 35 readily packed in a small space for shipping or storage when the legs have been removed.

With these objects, and the obvious advantages resulting therefrom in view, the invention consists in the novel features of construction, combination and arrangement of parts which will be hereinafter more particularly described and claimed.

In the accompanying drawings:

Figure 1 is a plan view of my invention 45 embodied in a table bowling game apparatus, the same being viewed from above.

Fig. 2 is a similar view of the under side of the table apparatus.

Fig. 3 represents a vertical longitudinal 50 sectional view.

Fig. 4 is a vertical transverse section, and

Fig. 5 is a detail longitudinal section through the bottom end of a pin showing the

manner of attaching a portion of the pin resetting mechanism thereto. 55

As hereinbefore indicated the invention in the present instance is embodied in a table apparatus, but it is to be understood that the several features thereof may be easily and effectively incorporated in a standard floor bowling alley. Likewise it will be appreciated that various details in the form and proportion and in the relationship of the several parts may be made without departing from or sacrificing any of the features of the invention. Referring more particularly to the accompanying drawings, the numeral 1 designates a table supported at a proper height by legs 2 and having a central longitudinally extending alleyway 3, at 70 each longitudinal side of which is a gutter 4 as is customary in most ten pin bowling games. A retaining rim 5 extends around the opposite sides and across one end of the table, the opposite end having a transversely 75 extending ball receiving pocket 6.

A plurality, preferably ten, of pins 7 are arranged at the last mentioned end of the table on the alleyway 3 and are disposed in a recess 8 formed in the latter, this recess 80 having a bottom 9 disposed a sufficient distance below the surface of the alleyway 3 to substantially house the pins 7 when the same are in their prone position.

When the pins 7 are stood in upright position, each of them covers an opening 10 disposed through the bottom 9 of the recess 8 and is adapted to slidably receive a flexible cord or the like 11. The pin attaching end of each of the cords 11 extends into a longitudinal bore 12 formed in the bottom end 90 of the pins, the inner end of this bore being open through the side of the pins as at 13. To connect the cords 11 to the pins, the ends thereof are inserted into the bore 12 and after washers 14 are placed therearound, 95 the same are knotted as at 15. A relatively loose connection is thus formed between the flexible cords 11 and the several pins 7 which are permitted to have a relatively rotary or turning action with respect to the former.

A ball or other round object is used for knocking down the upright pins 7 and when in use is projected forcibly down the alleyway 3 toward the pins. After the pins have 105

been knocked to prone position they are reset into an upright position by the resetting mechanism of which the flexible cords 11 form a part. The rest of the mechanism 5 includes a reciprocative head 16 movable longitudinally of the table and beneath the same, a plurality of, one for each of the pins 7, relatively rigid rods 17, and an operating handle 18. The reciprocative head 16 being 10 disposed intermediate the ends of the table, the handle 18 is projected from said head to a point adjacent the front end of said table. The handle is guided in its longitudinal movements by guide clips 19 secured 15 to the under surface of said table.

The rods 17 are adjustably secured in the head 16, and have their intermediate portions slidably supported on a transverse guide rod 20. The ends of the rods 17 opposite their connection with the head 16 are secured to the flexible cords 11 whereby the several pins 7 may be collectively and simultaneously reset from prone to upright position by the proper manipulation of the 25 handle 18.

The several flexible cords 11 are trained and guided about a plurality of guide elements in the form of rods 21. (See Fig. 2.) All of the parts which have just been referred to, namely the head 16, the handle 18, the rods 20 and the means for supporting and guiding the same, and the means for guiding the flexible cords 11, are located below the table 1, and are therefore normally 35 out of sight.

Considerable difficulty is sometimes experienced in quickly returning the pins from prone to upright position in view of the peculiar action which takes place between the 40 annular pin bottoms and the flat surface of the bottom of the recess 8, there being a frequent tendency on the part of the pins to wobble considerably while being disposed in playing or upright position. As a result 45 I have provided a plurality of metallic leverage ribs 22, the same being disposed transversely of the table 1 within said recess 8. Inasmuch as the pins 7 are arranged in transverse rows, I dispose one of the ribs 50 22 adjacent to, and to the rear of, each row of pins when the same are in upright position. Thus when the pins have been knocked down into the recess 8, their lower or bottom end portions rest upon the ribs 22. 55 Now when the handle 18 is moved outwardly with a consequent shifting of the head 16 and the flexible cords 11, it will be seen that a lever action is exerted by the several ribs 22 to more quickly seat the pins in 60 upright position.

This coöperation between the pin resetting mechanism and the ribs 22 is further increased therebetween by the addition of longitudinally extending ribs 23. These 65 ribs are positioned longitudinally of the al-

leyway 3 and are located in position one on each side of each longitudinal row of pins. Each of said pins at the points where it engages the ribs 22 and 23, is provided with an annular wear band 24.

The article which has been projected toward the pins 7 is permitted to enter the ball receiving pocket 6 from the rear end of the table 1 from whence it may be returned to the opposite end of the table by a 70 return chute 25. From Figs. 3 and 4 it will be seen that this chute consists of a relatively narrow inclined grooved strip hinged as at 26 to the discharge end of the pocket 6. When the apparatus is in use the opposite or 75 free end of the chute is placed below the bottom of the table 1 and is held and supported in this position by a swinging bracket 27. However, when the apparatus is to be shipped or stored the legs 2 are removed 80 and the chute 25 folded against the table bottom, the bracket 27 occupying the broken line position illustrated in Fig. 3. A very compact table is the result of this.

What is claimed is:

1. In a game apparatus, a supporting floor, a pin disposed on said floor and adapted to be knocked from upright to prone position and to be disposed substantially longitudinally of the floor when in the last 95 mentioned position, a rib disposed transversely of the floor, the pin resting thereon when in prone position, and means coöperating with said rib to move the pin from prone to upright position.

2. In a game apparatus, a floor provided with a pin receiving recess, a pin disposed in said recess and resting on the bottom thereof, said pin being relatively housed therein when in prone position, a rib disposed transversely of the floor in said recess and below the floor surface, the pin resting on said rib when in prone position, and means coöperating with said rib to raise the pin from prone to upright position.

3. In a game apparatus, a supporting floor, a pin disposed on said floor and adapted to be knocked from upright to prone position and to be disposed substantially longitudinally of the floor when in the last 115 mentioned position, a rib disposed transversely of the floor, the pin resting thereon when in prone position, a pair of ribs extended longitudinally of the floor, the pin resting therebetween when in prone position, and means coöperating with said ribs to raise the pin from prone to upright position.

4. In a game apparatus, a supporting floor, a pin disposed on said floor and adapted 125 to be knocked from upright to prone position and to be disposed substantially longitudinally of the floor when in the last mentioned position, a metallic rib disposed transversely of the floor and having the pin 130

resting thereon when in prone position, a wear band around the portion of the pin which engages said rib, and means coöperating with said rib to raise the pin from 5 prone to upright position.

5. In a game apparatus, a floor provided with an opening therethrough, a pin adapted to stand in upright position on said floor and to be knocked to prone position, a movable cross-head, a relatively rigid rod extending from the head, a transverse guide 10 slidably supporting the intermediate portion of the rod, and a flexible connection between the end of the rod and the pin, 15 said connection being extended through said opening.

6. In a game apparatus, a floor adapted

to have pins placed thereon at one end and balls or the like rolled thereover toward 20 said pins, a ball receiving pocket at the pin end of the floor, a return chute hinged at one end to the outlet of said ball pocket, the chute being inclined when in use and the end opposite the hinged end being disposed below the end of the floor opposite 25 the pin end, and means for moving the last end of the chute into the under side of the floor when not in use.

In testimony that I claim the foregoing I have hereunto set my hand at Milwaukee, 30 in the county of Milwaukee and State of Wisconsin.

HUGO LOEWENBACH.
